RAIL CROSSING

James H. Asselin, Winnetka, Ill.

Application July 19, 1945, Serial No. 605,989

8 Claims. (Cl. 246—467)

1

My invention has to do with improvements in rail crossing structures.

As a train moves along on a section of track it sets up in the track a vertical up-and-down wave or floating motion of the rails. In prior crossing constructions this motion has resulted in loosening the hold down means and in excessive wear on the bracing, ties and ballast. Most prior constructions were based on rigidity of track, but rigidity could not be maintained, and frequent repair and maintenance was required.

An object of my invention is to recognize the rail wave motion which is inherent in train movement and to control such motion rather than eliminate it, particularly, at the crossings. This results in less breakage and wear of the joints and consequently a reduction in maintenance and repair.

In accordance with my invention, wave motion in the rails is permitted to a limited degree. By securing the rail assembly structure to a solid steel base plate in such a manner as to permit limited relative movement between the rail assembly structure and the base plate, only a small portion of such movement is transmitted below the plate, to be absorbed by the ties and ballast.

An object of my invention is to provide a one-piece steel crossing base with rails and fillers secured together and to the base without the use of bolts or similar securing devices.

Another object of my invention is to provide a rail crossing having a one-piece steel base with integral hold down rail flange guide elements.

Another object of my invention is to provide in a rail crossing having a one-piece steel base and integral hold down rail flange guide elements, rail assemblies laterally braced and secured, by brace members without bolts or similar securing devices.

A further object of my invention is to provide a rail crossing structure wherein rails and fillers are locked in place on a base by rail braces and hold down integral rail flange guides which tie the entire crossing structure into one unit without bolts and at the same time permit a limited relative movement of the rails with reference to the base.

A further object of my invention is to provide in a rail crossing external and internal rails and fillers which are interchangeable in four sides of the crossing.

Further objects are improvement and simplification of rail-crossing structures, including easy replacement of worn or fractured elements, secure interlocking of the component parts, the maintaining of track gauge and alignment of crossing angle, the provision of elasticity and sound-deadening and other features of advan-

2

tage which will be apparent to those skilled in the construction and maintenance of railroad track.

A preferred embodiment of my invention is illustrated by way of example, in the accompanying drawings, wherein:

Fig. 1 is a plan of a completely assembled rail crossing;

Fig. 2 is a plan of a one-piece base plate for the crossing;

Fig. 3 is a cross section of the rail assemblies showing in elevation the transverse brace members;

Fig. 4 is a plan of one of the transverse brace members in position and to an enlarged scale; and

Fig. 5 is an exploded plan of the rail assemblies at one corner of the base plate.

My crossing comprises a one-piece base plate 10 which is shown in Fig. 2. The base plate 10 includes integral extensions 11 on each corner thereof. Permanently attached to the base plate 10, by welding or the like, are hold down guides 12, 13. Also attached by welding or the like to the base plate 10 are stop members 14 and 16 which cooperate with or form a part of the brace structure 15 shown in Figs. 1 and 3. The base plate or frame 10 is made, preferably, of a single piece of rolled steel or in any manner whereby it functions, when in use, as a one-piece integral base structure. The hold down guides 12, 13 and the brace stop members 14, 16 are permanently secured to the base plate so as to form an integral part thereof.

A cross section of the rail assemblies is shown in Fig. 3. Each assembly comprises a running rail 17, a false flange riser rail 18 and a guard rail 19. Filler members 20 are provided between the rails 17 and 18 and flange-way filler members 21 are provided between the rails 17 and 19. The flange-way filler member is cut away or recessed at 22 to provide flange clearance. To provide the desired spacing between the rails, the inner base flange of rail 18 is cut away at 23 so that the top of the rail abuts the top of the running rail. The inner base flange of the guard rail 19 is cut away at 24 to provide the proper spacing between it and the running rail 17.

The rail assemblies including the three rails and the two fillers are not secured to each other when in position on the base plate. Temporary securing means such as bolts may be provided to hold them in assembled relation until they are positioned on the base plate. However, they are restrained from transverse separation when in position on the base plate by brace members 15 placed on each side of each assembly. These brace members 15 are shown in Figs. 3 and 4 and each comprises a member 25, a wedge mem-

ber 26 having a projecting member 27, and a cotter pin 28. The brace members 25, 26 are positioned to engage the stop members 14 and 16 as shown in Fig. 4. The stop member 14 includes a recess 29 to receive the projecting member 27 of the wedge 26. The brace member 25 is positioned against the stop member 16, and the wedge 26 is driven into position between brace member 25 and the stop member 14. A series of holes 30 are provided at the narrow end of the wedge member 26 in the projection 27 to receive the cotter pin 28 to hold the wedge in position. The brace member 25 is shaped so that it engages the top of the outer base flange of the guard rail at 31 and beneath the head of the guard rail at 32.

The rail assemblies comprise interchangeable inner assemblies 33, 34, 35 and 36 as shown in Fig. 1. These inner assemblies are first slid in place on the base plate 10 in the assembling process. The hold down guides 12 and 13 have portions 37 (Fig. 3) spaced from the base plate so as to receive with slight clearance the outer base flanges of the rails 18 and 19 when the assemblies are slid onto the base plate in a direction along their longitudinal axes. The inner assemblies are positioned so that their ends are spaced from the gauge lines, which coincide with the inner edge of the top of the running rails 17. This spacing is the width provided for the flange-way, as shown in Fig. 3.

Rail assemblies 38 and 39 are provided at each corner which include short sections 18a, 19a, 20a, 21a of the false flange riser rail, the guard rail and the two filler members, respectively, and a somewhat longer section 17a of the running rail. The guard rail section 19a may be cut away at 41 to assure proper clearance for the wheel flange. These assemblies are slid into position on the base plate in the same relationship to the hold down guides as the four inner assemblies. The view in Fig. 5 shows a rail assembly 39 in proper position while the adjacent rail assemblies 34, 36 and 38 have been moved away from the point of intersection of the gauge lines to illustrate the end structure of the respective rail assemblies. When in position these corner assemblies are in abutting relation with each other and with the inner assemblies at their point of intersection. This relationship is such as to provide clearance through the intersection for the flange-way. After the corner assemblies 38 and 39 have been slid into position they are locked in place against longitudinal movement on the base plate. Stop members 40 are welded in place on the base and prevent movement of these assemblies in a direction of their longitudinal axes except for the running rail 17a. The running rail 17a being somewhat longer abuts the running rail of the main line and thus is prevented from moving longitudinally. The positioning of the corner assemblies locks the inner assemblies in proper position and prevents them from moving in the direction of their longitudinal axes. All the rail assemblies are then secured against transverse movement by the proper positioning of the brace members 15 as shown in Fig. 1.

The brace members 15 are placed opposite each other and restrain movement of the assemblies in a transverse direction. The construction of these brace members is such that a limited vertical movement of the rail assemblies is permitted. In this manner the rail wave motion which is inherent in train movement is not eliminated but is controlled. The motion is permitted to a lim-

ited degree. This construction does not involve any bolts or welding or other securing means between the brace members and the rail assemblies.

In order to cushion the movement of both the base plate and the rail assemblies, resilient means are provided between the rail assemblies and the base plate and beneath the base plate. As shown in Fig. 3, a resilient coated fabric 42 is provided beneath the base flanges of the rail assembly members. A resilient cushion member 43 of rubber or the like is provided beneath the base plate 10.

While the illustrated embodiment of my invention is shown applied to a right angle crossing it will be apparent that my invention is applicable to a crossing at an oblique angle.

The specific abutting relationship of the rail assemblies at the points of intersection which is illustrated is preferred in order to obtain the maximum of interchangeability of the assemblies and their component parts, but it is contemplated that the relationship may be modified for reasons of fabrication of parts or the like or because of special conditions at the point of crossing and the specific relationship is to be taken as illustrative only.

The stop members 40 may be welded to the base plate 10 or otherwise provided thereon when the hold down guides 12, 13 and stop members 14, 16 are provided on the base plate, that is, prior to placing the respective rail assemblies on the base plate. When the respective assemblies are then placed on the base plate 10 the component parts of the assemblies may be slid into place, separately, with the running rail sections inserted last. This arrangement eliminates all welding at the time when the crossing is installed.

Modification of the structure and changes in the materials within the scope of my invention will be apparent to those skilled in the art.

I claim:

1. A railway crossing for providing a connection between intersecting main track sections comprising a one-piece base frame having portions extending beyond the sides thereof in line with the main track sections, integral hold down flange guides spaced along said base frame, short inner rail assemblies aligned with said main track sections and having outer flanges engaged beneath certain of said hold down flange guides, other rail assemblies at each corner engaging the ends of said inner rail assemblies and connecting the inner rail assemblies with the main track sections, said other rail assemblies having outer flanges engaged beneath certain of said hold down flanges, stop members secured to said base extensions and engaging the outer ends of said other rail assemblies to prevent longitudinal movement of said rail assemblies and oppositely disposed brace members anchored to said base member, said brace members engaging the rail assemblies laterally to prevent transverse movement while permitting limited vertical movement with respect to said base member.

2. A railway crossing for providing a connection between intersecting main track sections comprising a one-piece base member having portions extending outwardly beyond the sides thereof in line with said main track sections, spaced integral hold down flange guide members on said base member, inner rail assemblies on said base member in alignment with said main track sections, outer rail assemblies on said base member connecting the inner rail assemblies with the

main track sections, said rail assemblies having outer base flanges received beneath said hold down flange guide members, means on the outwardly extending base member portions engaging the outer rail assemblies to prevent longitudinal movement of said rail assemblies on the base member, lateral brace means engaging said base member and the rail assemblies to prevent movement of the assemblies laterally of said base member and to permit limited vertical movement of said rail assemblies.

3. In a railway crossing structure, a one-piece base frame, integral hold down flange guides spaced along said base frame, a rail assembly disposed on said frame between said hold down flange guides comprising a running rail, a reinforcing rail along the outside of the running rail, a rail filler member between said running rail and said reinforcing rail, a guard rail spaced from said running rail along the inside of said running rail, a flange-way filler member between said running rail and said guard rail, a recess in the top of said flange-way filler member which is aligned with the space between said rails to provide a flange-way for the wheel flange, said reinforcing rail and said guard rail having outer base flange members slidably received beneath the hold down flange guides, brace members engaging the outer sides of the reinforcing rail and the guard rail, respectively, and extending outwardly, brace stop members integral with said one-piece base frame, wedge members engaging the outwardly extending brace members and the brace stop members, and end stop members for said rail assembly on said base frame, whereby the rail assembly is locked to the said base frame without the use of bolts or similar securing means.

4. In a railway crossing structure, a one-piece base frame, integral hold down flange guides spaced along said base frame, a rail assembly disposed on said base frame between said hold down flange guides comprising a running rail, a reinforcing rail along the outside of the running rail, said reinforcing rail having a base flange cut away and the head in engagement with the head of the running rail, a rail filler member between said running rail and said reinforcing rail, a guard rail spaced from said running rail along the inside of said running rail, a flange-way filler member between said running rail and said guard rail, a recess in the top of said flange-way filler member which is aligned with the space between said rails to provide a flange-way for the wheel flange, said reinforcing rail and said guard rail having outer base flange members slidably received beneath the hold down flange guides, brace members engaging the outer sides of the reinforcing rail and the guard rail and extending outwardly, brace stop members integral with said one-piece base frame, wedge members engaging the outwardly extending brace members and the brace stop members, and end stop means for said rail assembly on said base frame, whereby the rail assembly is locked to the said base frame without the use of bolts or similar securing means.

5. In a rail crossing structure, a one-piece base member, laterally and longitudinally spaced integral hold down flange guides thereon, rail assembly sections adapted to be loosely received in said hold down flange guides, said rail assembly sections comprising a running rail, a reinforcing rail having its lower flange cut away to accommodate a flange of the running rail whereby the head of said reinforcing rail is in abutting

relation with the head of the running rail, an unsecured filler member between the webs of said rails, a guard rail spaced from said running rail to provide a flange-way between said running rail and said guard rail, an unsecured flange-way filler between said running rail and said guard rail, securing members on opposite sides of said rail assembly sections having brace members, base stop members and wedge members, said brace members engaging said reinforcing rail and said guard rail respectively and said wedge members wedged between the brace members and said base stop members and end stop members for said rail assembly on said base member whereby to secure said rail assembly against lateral and longitudinal movement on the base member and permit limited vertical movement with respect thereto.

6. In a railway crossing structure, a one-piece base frame, integral hold down flange guide means spaced along said base frame, inner rail assemblies disposed along said base frame having outer base flange members positioned beneath said hold down flange guide means, transverse brace means comprising stop members integral with the base frame and wedge members engaging the outer sides of the rail assemblies and means including stop members on said base frame for preventing longitudinal movement of said rail assemblies whereby vertical movement of the assemblies is restrained and limited without the use of bolts or the like.

7. In a railway crossing structure as claimed in claim 6 wherein the outer corner rail assemblies are in abutting relation with the said inner rail assemblies.

8. In a railway crossing structure for providing a connection between intersecting main track sections, a one-piece base frame, flanged rail assemblies arranged in aligned connecting relation with the main track sections, guide means integral with said base frame for receiving said flanged rail assemblies and positioning the same on said base frame, and securing means limiting and restraining vertical movement of said rail assemblies relative to said base frame for connecting said rail assemblies to said base frame, said securing means comprising longitudinally and transversely spaced members integral with said base frame, wedging elements engaging between said last mentioned members and said rail assemblies, and end stop means for said rail assemblies on said base frame whereby longitudinal and lateral movement of said assemblies relative to said base frame is prevented and said assemblies are secured on said base frame without the use of bolts.
